[57] CLAIM

The ornamental design for a toy spaceship, substantially as shown and described.

DESCRIPTION

FIG. 1 is a top plan view of a toy spaceship showing our new design;

FIG. 2 is a side elevational view thereof, the side opposite being substantially a mirror image thereof; and

FIG. 3 is a front elevational view thereof;

FIG. 4 is a rear elevational view thereof; and

FIG. 5 is a bottom plan view thereof.

Fig. 3.

Fig. 4.
